UNITED STATES PATENT OFFICE.

CHARLES ELKIN, OF NEW YORK, N. Y.

DESIGN FOR A PIPE-HOLDER.

No. 39,558.

Specification for Design.

Patented Sept. 22, 1908.

Application filed May 6, 1908. Serial No. 431,285. Term of patent 14 years.

To all whom it may concern:

Be it known that I, CHARLES ELKIN, a citizen of the United States, residing at New York, in the county of New York and State of New York, have invented or discovered a new, original, and ornamental Design for Pipe - Holders, of which the following is a specification, reference being had therein to the accompanying drawing.

The accompanying drawing is a perspective view of a pipe holder showing my new design.

The new design comprises a circular base tapering upwardly on irregular curved lines, said base being surmounted by a concave

holder the upper portion of which curves gracefully backward, as shown.

I claim:

An ornamental design for a pipe-holder comprising a base tapering upwardly on irregular curved lines and surmounted by a concave holder with a backwardly curved upper portion, as shown and described.

In testimony whereof I affix my signature, in presence of two witnesses.

CHARLES ELKIN.
